Patented Mar. 31, 1925.

UNITED STATES PATENT OFFICE.

OTTO LIEBKNECHT, OF FRANKFORT - ON - THE - MAIN, GERMANY, ASSIGNOR TO THE
ROESSLER & HASSLACHER COMPANY, OF NEW YORK, N. Y., A CORPORATION OF
NEW YORK.

PROCESS FOR THE ELECTROLYTICAL PRODUCTION OF CYANATES FROM CYANIDES.

No Drawing.

Application filed August 27, 1921. Serial No. 496,047.

To all whom it may concern:

Be it known that I, OTTO LIEBKNECHT, a citizen of the Republic of Germany, and a resident of Frankfort-on-the-Main, Germany, have invented a new and useful process for the Electrolytical Production of Cyanates from Cyanides (for which I filed application in Germany Jan. 15, 1919), of which the following is a specification.

10 Paterno & Pannain (*Gazetta Chimica Ital.* Vol. 34 (1904) part 2, pages 152-155) have described the electrolytic production of alkali cyanates from alkali cyanides. According to their statements, yields of over 15 80% of pure cyanate can be obtained with a cathode current density of 1-4 amps. to 1 dm^2 when working with an electrolyte containing, potassium cyanide 4-6 gram mol. / liter, potassium hydroxide 1 gram mol. 20 / liter.

A part of the cyanate crystallizes out during the electrolysis.

According to their experimental data using 72 g. of potassium cyanide for oxidation, 32 g. of potassium cyanate crystallized out during the course of the electrolysis and 42 gms. more were secured upon evaporating the mother liquor. Thus, the greater part of the material must be obtained by 30 evaporation causing considerable loss of cyanate due to decomposition.

These several disadvantages, I have found can be avoided by the use of much greater concentrations of free caustic alkali in the electrolyte. Further, I have found, that this alkali can be either wholly or partially replaced by soluble carbonates, especially potassium carbonate. However, it is always desirable to add some caustic alkali to such a carbonate solution. In this way, I obtain practically all of the cyanate in solid form directly during the course of the electrolysis and I am thus enabled by the intermittent or constant additions of cyanide 40 to make my process a continuous one. (Note: The solubility of alkali cyanate in a 30% caustic soda solution is $\frac{1}{2}\%$). A further advantage of my process results from the large increase of anode current density 45 which I am able to use, being limited only by the current carrying capacity of the electrodes themselves.

Thus, in my new process using a platinum gauze anode, I am able to use from 5000

to 6000 A/M² as compared with a current of 100 to 400 A/M² used in the earlier process. In addition to this, with the former process, the yield of cyanate drops with increasing current density and a dark colored product of such bad appearances is produced that the process is not used in commercial practice. On the other hand, by using my new process, even at the very high current densities mentioned no decrease in the yield of cyanate is found, and an absolutely pure white product is obtained. The use of this high current density is of further advantage because of the smaller platinum anode investment required.

Now the greater portion of platinum thus required is used up in the anode connections. Trials to replace this platinum by other metals did not succeed at first. The strong alkali of the electrolyte make the use of aluminum and zinc out of the question. Nickel and iron answered this purpose without serious metal losses but gave a discolored product of inferior quality, and at a considerably decreased current efficiency. Copper was then tried and found to be a suitable metal both for current distributors and connectors, the cyanate so obtained being white while the current yield equalled that when only platinum was used. In other details the apparatus can be constructed as described in the literature.

Preferably the electrolyte is continuously kept nearly saturated with cyanide during electrolysis, except when concluding a run, when all the cyanide present is oxidized to cyanate, thereby decreasing the losses of cyanide in the mother liquor.

As an illustration of the process, the following experiment is described. The electrolyte consists of 3 liters of a 27% solution of caustic soda, together with the given quantity of sodium cyanide which it is desired to oxidize to cyanate. This can either be added at one time up to saturation or at intervals during the course of the electrolysis. The anode consists of platinum gauze or screen of 100 cm^2 area. The cathodes consist of iron. A current of 65 amperes is used. The temperature of the electrolyte should be maintained at about 50° C. When the calculated quantity of current needed to convert the cyanide to cyanate has been supplied, the electrolysis

is discontinued. The electrolyte is then cooled to 10-12° C., and the cyanate is recovered by filtering, an excellent current and material yield being secured.

5. What I claim is:

1. A process for production of alkali cyanates by electrolysis of an alkaline solution containing cyanides.
2. A process for production of alkali cyanates by electrolysis of an alkaline solution containing cyanides and more than one gram mol. per liter of combined caustic alkali and alkali carbonate.
3. A process for production of alkali cyanates by electrolysis of an alkaline solution containing cyanides at a current density of more than 400 amperes per square meter.
4. A process for production of alkali cyanates by electrolysis of an alkaline solution containing cyanides using copper as the anodic conducting and distributing member.
5. A continuous process for the production of alkali cyanates by electrolysis of an alkaline cyanide solution, more cyanide being added and the precipitated cyanate being removed periodically.
6. A continuous process for the produc-

tion of alkali cyanates by electrolysis of an alkaline cyanide solution, containing more than one gram mol. of combined caustic alkali and alkali carbonate, more cyanide being added and the precipitated cyanate being removed periodically.

7. A continuous process for the production of alkali cyanates by electrolysis of an alkaline cyanide solution, at a current density of more than 400 amperes per square meter, more cyanide being added and the precipitated cyanate being removed periodically.

8. A continuous process for the production of alkali cyanates by electrolysis of an alkaline cyanide solution, using copper as the anodic conducting and distributing member, more cyanide being added and the precipitated cyanate being removed periodically.

In testimony whereof I have signed my name to this specification in the presence of two subscribing witnesses.

OTTO LIEBKNECHT.
